J. H. ROYALL.

WHEELBARROW.

APPLICATION FILED JULY 16, 1913.

1,137,425.

Patented Apr. 27, 1915.

UNITED STATES PATENT OFFICE.

JOHN HALL ROYALL, OF WAKE FOREST, NORTH CAROLINA.

WHEELBARROW.

1,137,425.

Specification of Letters Patent. Patented Apr. 27, 1915.

Application filed July 16, 1913. Serial No. 779,274.

To all whom it may concern:

Be it known that I, JOHN H. ROYALL, a citizen of the United States, and a resident of Wake Forest, in the county of Wake and State of North Carolina, have invented certain new and useful Improvements in Wheelbarrows, of which the following is a specification.

My invention relates to improvements in wheelbarrows, and it consists in the combinations, constructions and arrangements herein described.

An object of my invention is to provide a device having sides of very light material which can be brought into position, or removed therefrom and which, when removed, are still carried by the bottom portion of the device, so that there is never the necessity of hunting for sides which have been misplaced.

A further object of my invention is to provide novel means for supporting the sides, these means including hinged supporting members which may be folded into sockets in the frame of the wheelbarrow.

A further object of my invention is to provide a novel form of dumping means which will obviate the necessity of removing one of the sides during the act of dumping.

Other objects and advantages will appear in the following specification, and the novel features of the device will be particularly pointed out in the appended claims.

My invention is illustrated in the accompanying drawings forming part of this application, in which—

Figure 1 is a side view of the device. Fig. 2 is a plan view. Fig. 3 is a section along the line 3—3 of Fig. 1. Fig. 4 is a section along the line 4—4 of Fig. 1. Fig. 5 is a perspective view of the upper part of one of the flexible sides. Fig. 6 is a detail view showing the hinged post. Fig. 7 is a detail sectional view showing the spring holding member.

In carrying out my invention I provide a device having the converging main frame members 1 and 2. The wheel 3 is rotatably carried at the ends of the members 1 and 2. Handles 1^x and 2^x are provided at the opposite ends of the members 1 and 2. Legs 3 are secured to the side frame members for supporting the device. A front board 4 is secured to front posts 5. Beneath the mem-

bers 1 and 2 are cross members 6 and 7. Between the cross members 6 and 7 beneath the main frame member 1 is disposed a spring roller 8 having thereon a flexible curtain or side member which is preferably made of very heavy cotton duct or similar material. This side member which I have designated as 9, passes through an opening 10 between the bottom and the main frame member 1. The upper end of the flexible member 9 is hemmed to provide a loop through which a suspension rod 11 is passed, this being preferably a steel or iron bar. The rod is provided with a downwardly turned end 11^x. On the opposite side of the device is a roller 8¹ and a flexible curtain 9¹ similar to the curtain 9. Hingedly supported upon the main frame members 1 and 2 are foldable supports 12 and 12¹. These supports are provided with hinges 13 and arranged to enter sockets or recesses 14 in the members 1 and 2 respectively, so as to lie flush with the upper part of these frame members.

The bottom of the wheelbarrow comprises two boards 15 and 16 which are hinged at their outer edges and which are normally supported at their contiguous edges by a rod 17 which passes through the cross member 6 and is threaded into the cross member 7.

From the foregoing description of the various parts of the device the operation thereof may be readily understood.

In using the wheelbarrow without the flexible sides the posts 12 and 12¹ are let down into their sockets and the flexible sides are lowered. They are carried upon the spring rollers 8 and 8¹ and when needed the posts 12 and 12¹ are swung upwardly, the sides are lifted, one end of the bar 11 is placed upon a spring member 18 which is secured to the post 5 in the manner shown in Fig. 7. The other end of the rod 11 is placed in a groove at the top of the member 12 with the extension 11^x projecting over as shown in Fig. 1. This locks the upright 12 in position. When it is desired to dump the wheelbarrow the rod 17 may be withdrawn, and the bottom members 15 and 16 will therefore swing downwardly, thus emptying the wheelbarrow of its contents, and obviating the necessity of lowering the sides to dump the contents.

A device constructed according to this in-

vention is of light weight and the sides are always in a position to be immediately available.

I claim:

- 5 1. In a wheelbarrow, a frame comprising a pair of converging members and cross members secured to said converging members underneath the latter, integral handles for said frame, the converging members of the frame each having a socket or recess, stationary front posts carried by said frame, a post hinged to each converging member of the frame and adapted to enter said recess, a roller carried by said cross members underneath each of said converging frame members and flexible side sheets carried by said rollers and arranged to be supported in position by said hinged supports at one end and by said front posts at the other.
- 10 15 20 2. In a wheelbarrow, a frame, stationary front posts carried by said frame, hinged

rear posts carried by the frame, rollers disposed underneath the frame, and flexible side sheets carried by said rollers and arranged to be supported in position by said hinged supports at one end and by said front posts at the other.

25 3. In a wheelbarrow, a frame, stationary front posts carried by said frame, hinged rear posts carried by the frame, rollers disposed underneath the frame, flexible side sheets carried by said rollers, a supporting bar for each of said side sheets, one end of said supporting bar being bent laterally to engage and to be supported by said hinged post, and the other end of the bar being supported by one of said front posts.

JOHN HALL ROYALL.
